UNITED STATES PATENT OFFICE.

WALTER J. BLIFFERT, OF MILWAUKEE, WISCONSIN.

AIR AND FUEL HEATER.

Application filed January 28, 1924. Serial No. 639,077.

To all whom it may concern:

Be it known that I, WALTER J. BLIFFERT, a citizen of the United States, and resident of Milwaukee, in the county of Milwaukee, 5 and State of Wisconsin, have invented new and useful Improvements in Air and Fuel Heaters, of which the following is a description, reference being had to the accompanying drawings, which are a part of this specification.

This invention relates to improvements in carburetor air heating devices.

It is one of the objects of the present invention to provide a device which will 15 conduct hot gas from the exhaust of a vehicle engine and introduce it against the exterior of a carburetor bowl to heat the same.

A further object of the invention is to 20 provide a device which will introduce heated air directly into a carburetor, thereby facilitating the vaporization of the fuel within the carburetor.

A further object of the invention is to 25 provide an attachment for an engine exhaust pipe adapted to conduct air to the carburetor and arranged so that the air conducted by the attachment must come in contact with the exhaust pipe and be heated 30 thereby.

A further object of the invention is to 35 provide a device of the class described which can be readily attached to a motor vehicle engine without any material alteration thereof.

A further object of the invention is to 40 provide a device of the class described which is of very simple construction, is inexpensive to manufacture, is strong and durable, and is well adapted for the purpose described.

With the above and other objects in view, 45 the invention consists of the improved carburetor air heating device, and its parts and combinations as set forth in the claims and all equivalents thereof.

In the accompanying drawing, in which the same reference characters indicate the same parts in all of the views:

50 Fig. 1 is a side view of the improved carburetor air heating device, the same being shown in connection with an engine exhaust pipe and a carburetor, parts being broken away and shown in section;

Fig. 2 is a detail view of the flexible tubing forming part of the device; and

Fig. 3 is a vertical sectional view taken on line 3—3 of Fig. 1.

Referring now more particularly to the accompanying drawing, it will be seen that 60 the numeral 5 represents the exhaust manifold of a motor vehicle engine, said manifold having an exhaust pipe portion 6.

The invention comprises a tubular pipe 7 adapted to be secured about the exhaust pipe 6 adjacent its point of junction with the manifold. The upper portion of the pipe 6 is enlarged, as shown in Fig. 3, and is formed in two parts, the portion 8 being clamped to the major portion 9 by means 70 of screw bolts 10 which pass through flanged portions 11 provided therefor. The lower portion of the enlarged part of the pipe 7 fits tightly against the exhaust pipe so as to prevent the admittance of air therein. 75 However, an opening 12 is provided in the upper portion to admit air and the air is free to circulate through the pipe, passing around and coming into contact with the exhaust pipe, as shown by the arrows in Fig. 80 3. The lower ends of the tubular pipe 7 connects with the carburetor 13 of the motor vehicle engine and opens into the same.

A flexible tubular member 14 is also provided, said member being shown in detail 85 in Fig. 2. One end of said member 14 is provided with an L-shaped head portion 15 which is threaded, as at 16, while the other end of the member is open. The major portion of said member 14 is adapted to be 90 confined within the pipe 7, as shown in Fig. 1, and its upper end portion passes through an aperture 17 formed in one side of the enlarged portion 9 of the pipe 7. The head portion 15 is screwed into an opening provided therefor in the exhaust manifold. The opposite end portion of the flexible member 14 passes through an aperture 18 in the lower part of the pipe 7 and the open end of the flexible member has an angular 95 disposition adjacent the carburetor bowl 19.

From the foregoing it will be seen that 100 hot gas is taken directly from the exhaust manifold, by the flexible tubing, and is discharged against the surface of the carburetor bowl. The pipe 7 takes in air through the opening 12 and said air must necessarily 105 come into contact with the portion of the

- exhaust pipe surrounded and be heated thereby. Also, the air is heated during its travel through the pipe by contact with the flexible tubing. The heated air is then discharged from the pipe 7 into the interior of the carburetor. It should be further noted that the lower end of the flexible tubing is provided with a cap 20 normally secured thereto by a wire 21, as shown in Fig. 1.
- 10 In hot weather, it has been found that the fuel within the carburetor will vaporize readily and it is then not necessary to heat the carburetor bowl. When this is the case, the lower end of the flexible tubing can be closed by said cap which is held in place by means of a cotter pin 22, as shown in Fig. 2.

Obviously, the device assists materially in the vaporization of fuel within the carburetor, is of very simple and novel construction, and is well adapted for the purpose set forth.

What I claim as my invention is:

1. An attachment for an internal combustion engine including an exhaust manifold having an aperture therein, and a carburetor, comprising a pipe opening into the carburetor and having an enlarged upper end portion, said enlarged portion surrounding a portion of the exhaust manifold, and a tubular member within the pipe and en-

tering the aperture in said exhaust manifold, the lower end portion of said tubular member projecting through the pipe adjacent the carburetor bowl.

2. An attachment for an internal combustion engine including an exhaust manifold having an aperture therein, and a carburetor, comprising a pipe connected to and opening into the carburetor and having an enlarged upper end portion formed in two sections detachably secured together, said enlarged portion also having an opening in the top thereof to admit air, the enlarged portion surrounding a portion of the exhaust manifold whereby the admitted air is heated, and a flexible tubular member having its major portion confined within said pipe, one end of said flexible member entering the aperture in the exhaust manifold, and the other end portion projecting through the pipe adjacent the carburetor bowl.

3. The combination with a carburetor and an engine exhaust manifold, of a pipe for conveying warm air into the carburetor, and a tubing having its major portion confined within said warm air pipe for directing exhaust gas against the exterior of the carburetor bowl.

In testimony whereof, I affix my signature.

WALTER J. BLIFFERT.
